US00D925577S

(12) **United States Design Patent** (10) **Patent No.:** **US D925,577 S**
(45) **Date of Patent:** **** Jul. 20, 2021**

(54) **DISPLAY SCREEN OR PORTION THEREOF WITH GRAPHICAL USER INTERFACE**

(71) Applicant: **Apple Inc.**, Cupertino, CA (US)

(72) Inventors: **Patrick Lee Coffman**, San Francisco, CA (US); **Raymond Sepulveda**, San Jose, CA (US); **Chun Kin Minor Wong**, Cupertino, CA (US)

(73) Assignee: **Apple Inc.**, Cupertino, CA (US)

(**) Term: **15 Years**

(21) Appl. No.: **29/741,754**

(22) Filed: **Jul. 15, 2020**

Related U.S. Application Data

(63) Continuation of application No. 29/710,764, filed on Oct. 25, 2019, now Pat. No. Des. 890,806, which is a (Continued)

(57) **CLAIM**

The ornamental design for a display screen or portion thereof with graphical user interface, as shown and described.

DESCRIPTION

The file of this patent contains at least one drawing/photograph executed in color. Copies of this patent with color drawing(s)/photograph(s) will be provided by the Office upon request and payment of the necessary fee.

The sole FIGURE is a display screen or portion thereof with graphical user interface showing our new design.

The peripheral dashed broken lines illustrate a display screen or portion thereof, and form no part of the claimed design. The dotted broken lines illustrate boundaries which form no part of the claimed design and the faded portions within the dotted broken lines form no part of the claimed design.
